UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed December 3, 1923. Serial No. 678,094.

The invention relates to draft gears of the friction type, applicable more especially in freight service; and its objects are to secure high efficiency and simplicity of construction.

A desirable form of embodiment of the invention is hereinafter described, and is illustrated in the accompanying drawings, in which

10 Fig. 1 is a central plan section of the gear, portions of the underframing of the car to which it is applied being shown in plan;

15 Fig. 2 is a central vertical longitudinal section of the gear, the coupler elements associated therewith being shown in elevation;

Fig. 3 is a view similar to Fig. 1, but the sectional portion thereof being taken on the line 3—3 of Fig. 2, and the gear being shown under full compression;

20 Figs. 4, 5 and 6 are views in perspective of wedging elements and one of the friction plates of the gear, the last figure being drawn to a reduced scale.

For the purpose of showing the manner 25 of applying the gear to a car, there are illustrated in the drawings conventional forms of center or draft sills at 10, a pair of draft lugs at 11, 11, a pair of buffing lugs at 12, 12, a coupler butt at 13, and a coupler 30 extension or yoke at 14. These elements do not form any part of the invention, and may take any desired and suitable form.

The improved gear comprises a pair of chambered followers 15, 16, cooperating, respectively, with the draft and buffing lugs and being normally spaced apart; two groups, 17, 18, of intercalating friction plates housed within the chambers of the followers; two sets of wedging elements, 40 each housed within one of the followers, generally designated, respectively, by the numerals 19, 20, interposed between the two groups of friction plates,—there being associated with each set of wedging elements 45 springs for normally holding the members thereof in wedging engagement; and a plurality of releasing springs which react between the two sets of friction plates of each group through the medium of transverse releasing bars. The friction plates, as 21, are 50 preferably all of like form, and are bifurcated in order to provide space for the releasing springs, as 22, which are shown as four in number, two being associated with 55 each group of plates.

The plates of the two sets of each group are longitudinally reversely arranged, and the releasing bars 23, 24, are located, respectively, at the inner ends of the plate slots, extend entirely across the gear and form seats for the releasing springs. The cross members of the bifurcated or U-shaped friction plates constitute shoulders for engagement by the releasing bars.

While it is desirable to form the plates as described, it is obvious that the physical union of the upper and lower section of each is not essential, it being necessary to the operation of the gear that each section be provided with a shoulder for cooperating with one of the releasing bars.

Each of the sets of wedges 19, 20, comprises two elements 25, 26, each having an outer flat face for bearing against the inner plate of one of the groups of friction plates. The wedging element 25 is seated against the cross member of the adjacent follower, and is apertured to accommodate the releasing bar at that end of the gear, which is at all times in engagement with the outer wall of this aperture by reason of the pressure of the releasing springs. The wedging element 26 is not engaged by either follower. It is substantially of the same form as the element 25, but is bifurcated to provide clearance for the releasing bar.

Both of the elements 25, 26, are provided adjacent their forward or thinner ends with instanding lugs 27, 28, 29, 30, which project beyond the planes of the wedging faces, and each is channeled, as shown at 31, in line with each of its lugs to provide clearance for the lugs of the companion element and chambers for the reception of springs 32, 33, which react between aligned lugs of the two elements. By the action of these springs the wedging faces of the two elements of each set are normally maintained in contact and the friction plates under compression. The inclination of the several wedging faces is considerably less than the angle of repose.

The length of the friction plates is such that when the gear is in release position their inner or closed ends are spaced slightly from the inner face of the adjacent follower, as shown in Fig. 1, their opposite ends terminating at such distance from the other follower that they do not make contact with its transverse wall when the gear is completely closed, as shown in Fig. 3.

In assembling the parts the two sets of friction plates are reversely disposed transversely of the gear. The two sets are so arranged relatively that the inner plate of 5 each group is in engagement with a wedging element 25 of the set which is secured within the follower with which that wedging element is associated, as shown in Fig. 3. As a result of this arrangement there is 10 but very slight relative movement between the wedging elements 25 and the friction plates against which they bear, while there is a maximum of relative movement between these plates and the elements 26. 15 For convenience in assembling the gear set screws 34 may be run into the aperture, as 35, in the wedge element 26 until it presses the lug 27, of the element 25, inwardly. This action compresses the springs 32, 33, and 20 hence lessens the width of the combined wedge element and permits its easy insertion between the two groups of friction plates. After such insertion the set-screw may be removed. 25 Upon the application of buffing stresses the follower 15 is moved backwardly, carrying with it the adjacent wedging element 25 and the releasing bar 24. Inasmuch as the friction plates are already under compression 30 by reason of the action of the springs 32, 33, the adjacent wedging element 26 is frictionally held and the angle of the friction faces being quite acute a maximum of wedging effort is instantly developed. The advancing 35 follower, coming at once into engagement with the rear ends of the friction plates which are secured within it, carries these plates backwardly against the frictional resistance between them and the other set of 40 plates. The wedging elements at the opposite or inner end of the gear are immediately forced into more intimate relation by reason of the friction developed between the inner plate of 45 the group 18 and the element 26 of that set, and the compressive action upon the friction plates is substantially the same at both ends of the gear. A card diagramming the 50 resistance of the gear would show a substantially instantaneous development of the maximum resistance, and this resistance remains constant until complete compression has occurred, for the reason that the friction between the wedge elements 26 and the plates 55 with which they are engaged does not change after the initial augmentation of the wedging pressure. Upon the cessation of buffing stresses the gear is promptly released by the action of the springs 22, which are of sufficient strength to instantly move outwardly 60 the wedge element 25 at the forward end of the gear, through the bar 23, which, it will be observed, is, during the compressive action, out of engagement with the shoulders 65 of the friction plates with which it cooperates. The two wedging elements are thus instantly separated sufficiently to reduce the compression upon the plates to the minimum. As soon as the retractive movement of the advance plates begins the wedging element 26 at the inner end of the gear is drawn 70 forwardly by the frictional engagement therewith of the plate having bearing upon it. The compression of the friction plates at the inner end of the gear is, therefore, 75 similarly instantly reduced to the minimum, and the complete release of the gear is at once effected.

The acute angle of the wedging faces to the axis of the gear not only insures a desirable instantaneous development of maximum pressure upon the plates, but makes it possible to use wedging elements of small transverse dimension, and consequently occupying but very little space, thus leaving a 80 large space at each side of these elements and permitting the use of a large number of friction plates without departing from the standard dimensions of the gear.

The action of the gear under the influence 85 of the stresses of draft is the same as in buffing, though, of course, in the reverse direction.

It will be noted that while the springs, as 90 32, 33, normally urge the wedging elements with which they are associated into engagement, their action is relieved by relative movement of these elements incident to the compression of the gear. These springs become at once active as the gear is released 95 and maintain the wedging elements in contact.

While the construction shown and described is highly efficient, it may be departed 100 from within the scope of the invention.

I claim as my invention—

1. In a draft gear, in combination a pair of opposed followers, frictional elements relatively movable responsive to the relative movement of the followers, two independent sets of compressing means relatively disposed longitudinally of the gear for forcing the friction elements together with substantially uniform pressure throughout the approaching movements of the followers, means against which the compressing means react laterally, means for limiting the outward movement of the friction elements, and means for restoring the parts to normal positions upon release of the gear.
2. In a draft gear, in combination, two opposed chambered followers, two groups of intercalating friction plates enclosed within the followers, the plates of each set of each group being endwise engageable by one of the followers, two sets of cooperating wedging elements interposed between the two groups of plates the members of each set frictionally engaging the inner plate of each group, one set being enclosed within each

follower, one element of each set of wedging elements being positively acted upon by the enclosing follower the other element being floating, means for holding the elements of each set in wedging engagement, and means for restoring the parts to normal position after compression.

3. In a draft gear, in combination, two opposed chambered followers, two groups of intercalating friction plates enclosed within the followers, the plates of each set of each group being endwise engageable by one of the followers, two sets of cooperating wedging elements interposed between the two groups of plates, one set enclosed within each follower, one element of each set of wedging elements being positively acted upon by the enclosing follower, the longitudinal positioning of the other wedging element of each set being dependent mainly on its frictional engagement with one of the friction plates, spring means normally urging the wedging elements of each set together and means for restoring the parts to normal position after compression.

4. In a draft gear, in combination, a group of intercalating friction plates, two independent sets of directly cooperating wedge elements applied one to each of the end portions of the plates, means for limiting the lateral outward movement of the plates, means against which the wedge sets react, means for advancing one of the wedges of either set on compression of the gear, and means for restoring the parts of the gear to normal positions after compression.

5. In a draft gear, in combination, a pair of casings, two groups of intercalating friction plates housed within the casings, two independent sets of wedge elements enclosed within the casings and interposed between the groups of plates, a spring reacting between the two elements of each set to urge them together, positive means for advancing or resisting the advance of one element of each set, the movement of the second element

being resisted by friction and means for restoring the parts to normal position after compression.

6. In a draft gear, in combination, two groups of intercalating friction plates, two independent sets of cooperating wedging elements interposed between the groups, one member of each set being adapted for positive engagement by a follower and the other member being floating, the members of the two sets being reversely arranged transversely of the gear, the parts being so arranged that each of the positively actuated wedging elements engages a plate associated with the same follower, the floating member engaging a plate associated with the other follower and means for restoring the parts to normal position after compression.

7. In a draft gear, in combination, a pair of followers, a pair of floating oppositely movable friction elements, each being positively engageable by one of the followers on compression of the gear, a pair of elements cooperating as wedges interposed between the friction elements and in frictional engagement therewith, one of such elements being positively associated with one of the followers, means for limiting outward movement of the friction elements, and means for restoring the parts to normal positions on release of the gear.

8. In a draft gear, in combination, a pair of opposed chambered followers, two groups of intercalating friction plates, one set of the plates of each group being endwise engageable with the end portion of one of the followers, two independent sets of cooperating wedges interposed respectively between the end portions of the groups of plates, the back faces of the wedges frictionally engaging the adjacent plate, springs normally urging the wedges of each plate into engagement, and releasing springs for restoring the gear parts to normal positions after compression of the gear.
